UNITED STATES PATENT OFFICE

FRANK R. MORRIS, OF BERKELEY, CALIFORNIA.

PERPETUAL CALENDAR.

1,286,058.

Specification of Letters Patent. Patented Nov. 26, 1918.

Application filed June 5, 1917. Serial No. 173,045.

To all whom it may concern:

Be it known that FRANK R. MORRIS, a citizen of the United States, residing at Berkeley, in the county of Alameda and State of California, has invented certain new and useful Improvements in Perpetual Calendars, of which the following is a specification.

This invention relates to calendars and has as its principal object the construction of such a device involving certain sliding scales which carry numbers that designate years and dates of the month and which, when properly set, relative to certain fixed designations of the months, will give the correct calendar for the desired month.

One of the principal objects of my present invention is to arrange the various numeral carrying slides in such a manner that the days of the week are arranged in their customary order, that is, with Sunday on the left and Saturday to the right.

A still further object of my invention is to so adapt the device that it may be used as a tip for a pencil or other writing instrument.

With these and other objects in view, the invention consists of certain novel features of construction, combinations and arrangements of parts hereinafter described and more specifically pointed out in the appended claims; it being understood that changes in form, proportion, size and minor details of construction within the scope of the claims may be resorted to without departing from the spirit of the invention or sacrificing any of the advantages thereof.

Referring to the drawing forming a part of this specification,

Fig. 1— is a view in front elevation of a calendar embodying my improved invention.

Fig. 2— is a view in rear elevation of the same.

Fig. 3— is a transverse view in cross section.

Fig. 4— is a view in front elevation of a modified form of a calendar having a more limited capacity than the one shown in Fig. 1.

Fig. 5— is a view in elevation of the calendar as applied to a cylindrical surface.

Fig. 6— is a view in section of the form shown in Fig. 5.

Fig. 7— is a view in front elevation of another modified form.

Fig. 8— is a developed view of the tables of figures used in connection with the form shown in Fig. 7.

Referring to corresponding parts of the several views by the same numerals of reference and more particularly to Figs. 1, 2 and 3, 1 denotes a flat container or frame formed of any suitable material such as paper-board, wood or metal. This frame is provided with upper and lower guide-ways 2 and 3 in which is slidably mounted the flat rectangular member 4.

The frame 1 is provided on the front with upper and lower openings 5 and 6 respectively, through which the surface of plate 4 may be viewed. The member 4 is in turn provided with guideways 7 and 8 in which is slidably mounted a card 9, the surface of which may be viewed through an opening 10 in card 9, which opening is directly under opening 5.

On the surface of container 1 adjacent the upper edge of opening 5 are provided the designations 11 for the days of the week beginning with Sunday and ending with Saturday, thus forming the heads for seven parallel columns. On the bridge piece 12 between the openings 5 and 6 are a like number of divisions in which are printed the months of the year as designated at 13.

That portion of the member 4 which is exposed to view through opening 6 is provided on its face with numbers 15, commencing at 00 and terminating with 99, these numbers representing the two terminal digits of the years. Certain of these numbers which are the terminals of leap year, are provided with distinguishing marks as shown at 14 which indicate that those numbers are to be used for the months of January and February of the leap years. For the other months of leap years the corresponding undesignated numbers are used.

On the face of member 4, above the bridge piece 12 but below the lower edge of opening 10, are provided numbers indicated by 15' which correspond to the initial two digits of the years. Both the numerals 15 and 15' are arranged between parallel lines 16 which are spaced at a distance equal to divisions which contain the days and the months.

Card 9 has six rows of figures arranged in eighteen vertical columns spaced the same as the days above opening 5. The figures designated by 16 run from 1 to 31 and are so

arranged that when viewed through the opening 5 a complete set of figures from 1 to 31 is visible. In other words, any seven adjoining columns will show consecutive numbering from 1 to 31. Card 9 is provided with pointers or indicators 19 and 20 which are used in setting the calendar.

A container 1 on the back is provided with narrow slots 21 and 22, the member 4 10 having a suitable tab or button which extends through slot 21, whereby this member may be shifted from side to side. Likewise card 9 is provided with a slot 23 which is in alinement with slot 22 and is provided 15 with a tab 25 extending through these two slots whereby the card 9 may be shifted in its guide-ways.

To set this form of calendar for any month within its capacity, the card 9 is 20 moved until either the indicator 19 or 20 points to the number 15 which designates the initial digits of the year and then the card 4 is moved until the terminal digits of the desired year are under the month for 25 which the calendar is to be set.

Thus, as shown in Fig. 1, the calendar is set for June 1917, since as previously described, the pointer 19 is opposite the digits 19 and in the lower opening, terminal digits 30 17 are under the month, June. It will be noted that the numerals designating the dates of the month, appear within the opening 10 in their customary relative order. If the calendar is to be set for January or 35 February of a leap year, then the specially designated numeral 14 for that year is brought under the desired month.

In the form shown in Fig. 4, the frame 30 is provided with a sliding card 31 and 40 has openings 32 and 33. Above opening 32 are printed the days of the week denoted by 34 and above opening 33, the month of the year, as shown in 35.

On the lower part of slide 31 are the numerals 36 denoting the years and on the upper part of this slide are numerals 37 denoting the days of the week. In this form, a slot 37' is provided through which extends a tab or other means 38 by which 45 the slide 31 may be moved. To set this 50 form of my calendar, it is only necessary to move the slide 31 until the year is under the corresponding month when the numerals 37 will appear in the opening 32 in their 55 proper relative position for that month.

In the cylindrical form shown in Fig. 5, a member 40 is provided having suitable means for retaining a revolute band 41. The latter is provided with openings 42 and 60 43 through which may be viewed the figures 44 and 45, the former denoting the days of the week, the latter the terminal numerals of the years of any given century or portion thereof. This form of calendar is merely 65 the form shown in Fig. 4 wrapped into a

cylinder and a stop 47 is provided for limiting the rotation of member 41. This device is set by turning the member 41 until the designation of the month, as denoted by 46, is above the column containing the terminal 70 numeral of the given century.

This latter form of my invention may be made very small and compact so that the same may fit over the end of a pencil furnishing a calendar which is readily acceptable and which it is not necessary to change separate slips of paper in order to keep it up to date. This form may also be provided with a suitable extension 49 which forms a retaining clip for the writing instrument. 75 Instead of making the numerals of limited extent and providing the stop 47, they may be printed as shown in Fig. 8, the length of the rows being just sufficient to encircle the supporting surface.

I claim as new and wish to cover by Letters Patent:

1. A calendar comprising a member having rectangular openings, a card movably mounted with respect to said openings, 90 designations carried by said member adjacent an edge of one of said openings representing the days of the weeks and adjacent a parallel edge of one of said openings representing the months, a set of figures indicating the days of the month carried by said card and a set of figures denoting years carried by said card, said figures being adapted to be viewed through the said openings.

2. A calendar comprising a member having rectangular openings, a card slidably mounted with respect to said openings, 100 designations carried by parallel edges of said openings denoting day of the week and month of the year, a set of figures denoting 105 years carried by said card, and a set of figures indicating days of the month carried by said card and movable with respect to said year figures, said day indicating figures and said year indicating figures being movable through said openings and movable parallel to said day and month designations.

3. A calendar comprising two relatively movable members, the outer of said members being provided with two sight openings, designations for the days of the week and months of the year arranged in seven headings above the upper and lower edges respectively, of said sight openings, the 115 inner of said members having parallel columns adapted to register with the headings above said openings, a third member movable with respect to said inner member and said inner member having an opening 120 through which said third member may be viewed, rows of figures denoting days of the month arranged in columns adapted to register with the aforesaid day headings and be viewed through the opening in said 125 130

inner member and the upper opening in said outer member, said figures being disposed so that any seven adjoining columns will read consecutively from one to thirty-one, 5 numerals denoting the terminal digits of the year arranged in the columns viewable through said lower opening and adapted to be brought in registry with the headings denoting months, a third group of figures 10 denoting the initial digits of the years arranged in said columns below the opening in said inner member and fixed markers carried by said third member adapted to be placed in registry with the initial digits of 15 the desired year in said third group.

4. A calendar comprising a member having rectangular openings, a card movably mounted with respect to said openings, a set 20 of figures denoting the days of the month and a set of figures indicating years carried by said card in a fixed relation to each

other and adapted to be viewed through said openings, day designations and month designations carried by said member along edges of said openings which are parallel 25 to the movement of the card therein.

5. A calendar comprising a member having rectangular openings, a card movably mounted back of said openings, a second card movably mounted in said first card 30 but normally held in fixed relation thereto, a set of year designations carried by one of said cards, a set of figures denoting days of the month carried by the other of said cards, said designations being viewable 35 through said openings, day designations and month designations carried along edges of said openings parallel to the movement of said card therein.

In testimony whereof I affix my signature. 40

FRANK R. MORRIS.
